UNITED STATES PATENT OFFICE.

EBENEZER D. HARRIS, JR., OF LANDER, WYOMING.

COLLAPSIBLE CRATE.

1,297,564.

Specification of Letters Patent. Patented Mar. 18, 1919.

Application filed July 22, 1918. Serial No. 246,155.

To all whom it may concern:

Be it known that I, EBENEZER D. HARRIS, Jr., a citizen of the United States, residing at Lander, in the county of Fremont and State of Wyoming, have invented certain new and useful Improvements in Collapsible Crates, of which the following is a specification.

This invention relates to wooden receptacles, and more especially to knock-down crates which are cylindrical or substantially so in contour; and the object of the same is to produce a collapsible crate or barrel capable of being folded into small compass 10 for storage or transportation.

This object is carried out by building the device in sections hingedly connected with each other on upright lines and increasing in width from one end of the series to the other, so that the smallest section may be folded in first, then the next, and so on.

The object of the invention is also carried out by making the heads of the crate or barrel foldable so that they may be stored 20 within the remainder of the structure.

Details of the preferred structure or form of this device are set forth in the following specification and claims, and attention is invited to the drawings herewith and in 30 which:

Figure 1 is a side elevation and

Fig. 2 a plan view of this improved barrel when its hoops are mounted on the exterior thereof, and

Fig. 3 and 4 are sectional details to amplify the attachment of the hoops and locate the position of the hinges therein,

Fig. 5 is an elevation and

Fig. 6 a cross section giving an edge view 40 of the fastening device or hasp for connecting the extremities of each exterior hoop,

Fig. 7 is a sectional view through the upper portion of the barrel, showing how the head is placed in position therein, and

Fig. 8 is an enlarged sectional detail of 45 one of the fastening buttons for the head,

Fig. 9 is a horizontal section through a set-up barrel with the hoops on the interior thereof, and

Fig. 10 is a plan view of the same when 50 some of the staves are omitted and the device becomes a crate,

Fig. 11 is an elevation of a portion of this crate,

Fig. 12 is a plan view of a portion of the 55 crate with the exterior hoop,

Fig. 13 shows the device when collapsed, the hoop being on the exterior, and

Fig. 14 shows the same when the hoop is 60 on the interior.

I may say at starting that where I refer herein to staves, I means both those elements which form parts of a barrel and have considerable bilge, and those straight elements which form part of a cylindrical container. 65 In either case also, the staves may lie side by side as when a closed barrel is to be formed and as shown in Fig. 7, or the staves or slats may be spaced as when an openwork crate is to be formed, as best seen in Fig. 10. If the container has heads at both ends it becomes in effect a barrel or crate, but if only the lower head is used then it may be called a tub. I do not wish to be limited 70 in this particular, nor as to the proportions and materials of parts, although by preference the staves and the heads are of wood.

The barrel shown in Figs. 2 and 13 is made up of twenty staves 1, arranged in a series of five sections of four each, and as 80 herein shown the staves in successive sections grow narrower and narrower so that the length of the sections decreases from one end of the series to the other. What may be called the longest section indicated at 85 2 in Fig. 13 is shown as made up of four staves 1 which are quite wide, although there is no reason why it might not be made up of five staves a little narrower or even perhaps of six. The next narrower 90 section indicated at 3 is at the top of Fig. 13, and the next narrower section overlies that numbered 2 at the bottom. So on to the shortest section of the series which is at the inside and is numbered 4. Around 95 these sections are strap metal hoops 5, there being always one at the top and another at the bottom of the barrel or container, and preferably at least one intermediate hoop as shown in Fig. 1. Each hoop is made in 100 sections corresponding with the width of the sections referred to, and its extremities are inturned as indicated at 6 so as to form leaves of a hinge, the knuckles 7 interengaging as usual to receive the pintle pin. The 105 leaves are notched into the staves 1 as indicated in Fig. 4, thereby producing a butt hinge so as to permit the staves to come edge to edge when the barrel structure is opened out, but to open no further. The 110 knuckles are quite within the barrel as seen at 7 in Fig. 7, and of course they stand at

the meeting lines between the several sections.

At the left edge of the widest section and the right edge of the narrowest, the hoops 5 are provided with fastening devices as seen in Figs. 5 and 6. One end of the hoop has a tongue 10 hinged thereto at 11 and provided with a roughened staple 12 and provided with a bent pin 13. The other end of the 10 hoop carries a hasp 14 hinged thereto at 15, and the hasp is provided with a slot 16, a notch 17, and a notch in its extremity as at 18. Riveted at 19 to the tongue is what might be called a spring hasp 24 provided 15 with a slot 26 and with another slot 28, and at its extremity with a hook 27. (This overlies the tongue, but is turned aside in Fig. 5 for clearness.) After the strap hoop has been drawn up tight, the tongue is laid 20 against the same near the free edge of the narrowest section, then the hasp 14 is laid over the tongue and its slot 16 passes over the staple 12 while its notch 18 engages the pin 13, and finally the spring hasp 24 is 25 laid over the tongue and its slot 26 passes over the staple 12 while its hook 27 engages the notch 17 and its slot 28 passes over the belt pin 13. The latter holds the parts temporarily, but by preference a padlock or the 30 like is passed through the protruding portion of the staple to hold the fastening device securely. However, it is quite possible that any other suitable means may be employed for connecting the ends of the strap 35 metal hoop.

It is quite possible that the hoops may be on the interior of the structure. This idea is illustrated in Fig. 9 where the numeral 5' designates the hoop made in sections, and 6' 40 its knuckles. Of course in this case the fastening device would have to be independent of the extremities of the hoop, and it must of necessity be on the exterior of the structure. An interior hoop is also shown in Fig. 45 14. The hoop placed on the interior avoids the necessity for carrying it through notches in the edges of the slats as seen in Fig. 4, because the knuckles are already on the inside. By omitting certain of the slats the structure 50 becomes a crate as best seen in Figs. 10 and 11. The interior hoop 5' is shown in Fig. 10 while the exterior hoop is shown in Fig. 12. The overlapping hasps 14 and 24 are shown in Fig. 11 where the crate is set 55 up, and the same is shown folded in Fig. 14.

As to the heads of the barrel, attention is invited to Figs. 2, 7, and 8. Each head is made up of panels 30, 31, and 32, the intermediate panel being wider than the others 60 and disposed between them. Across these several panels are extended the leaves 33 of hinges, which are connected by knuckles and pintles at the points 34 so that the head may fold as shown in Fig. 13. The extremities 65 of the leaves may be continued into points

indicated at 35 for embedding the interior of the body when set up. The intermediate and wider panel may carry buttons as indicated at 36 and shown in Fig. 8. As first suggested in this specification, there may be 70 heads at both ends of the structure, or if but the lowermost head is used the structure becomes a tub. The head is shown in Figs. 2 and 7, and the latter view indicates in dotted lines how its outer leaf 31 is first folded 75 onto its main leaf 30, after which the second outer leaf 32 is folded over in a manner which will be clear. When the structure is collapsed as indicated in Figs. 13 and 14, the head or heads will easily pack in the interior as shown, especially if the diameter of the case is a little less than half its entire height. When setting up a barrel to have two heads, the lower head is first opened out, then the body carried around it and the 80 lowermost hasp fastener latched and perhaps the ones next above it, but the others are left unlatched. The barrel is now filled to its capacity and the uppermost head put in, and finally the uppermost latch or latches 85 are fastened to complete the structure. When padlocks are fastened in the several staples, it will be impossible to remove either head until the padlocks are first removed.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. The herein described collapsible cylindrical container, the body thereof being made up of a series of sections, a plurality of strap metal hoops inclosing said sections and themselves made in sections corresponding in length with the width of the body sections, the extremities of the hoop sections being carried inward past the edges of the body sections and formed into interlocking 110 knuckles, pintle pins through said knuckles on the interior of the structure, and means for fastening the ends of the hoops which are not hinged to each other.

2. The herein described collapsible cylindrical container, the body thereof being made up of a series of sections growing narrower consecutively from one end of the series to the other, and hinges connecting the sections edge to edge, for the purpose set 115 forth.

3. The herein described collapsible cylindrical container, the body thereof being made up of a series of sections growing narrower consecutively from one end of the se- 120 125 130

ries to the other, a plurality of strap metal hoops inclosing said sections and themselves made in sections corresponding in length with the width of the body sections, hinges 5 between all hoop sections except at one point, and fastening means between the sections of the hoops at that point.

4. The herein described collapsible cylindrical container, the body thereof being 10 made up of a series of sections growing narrower consecutively from one end of the series to the other, a plurality of strap metal hoops inclosing said sections and themselves made in sections corresponding in length

with the width of the body sections, the extremities of the hoop sections being carried inward past the edges of the body sections and formed into interlocking knuckles, pin- 15 tle pins through said knuckles on the interior of the structure, and means for fasten- 20 ing the ends of the hoops which are not hinged to each other.

In testimony whereof I affix my signature in presence of two witnesses.
